UNITED STATES PATENT OFFICE.

EDWIN K. KREBS, OF SEITZLAND, PENNSYLVANIA.

TRAIN-PIPE COUPLING.

1,203,363.

Specification of Letters Patent. Patented Oct. 31, 1916.

Application filed October 29, 1915. Serial No. 58,629.

To all whom it may concern:

Be it known that I, EDWIN K. KREBS, a citizen of the United States, residing at Seitzland, in the county of York and State of Pennsylvania, have invented certain new and useful Improvements in Train-Pipe Couplings, of which the following is a specification.

This invention relates to an improved 10 train pipe coupling and the principal object of the invention is to provide a coupling so mounted that it may have sufficient movement to compensate for vertical and transverse movement when the train is moving 15 along the track and to further provide the coupler with an improved type of head mounted for universal movement so that the heads of the two couplers on connected cars will at all times be held in tight engagement 20 when the cars are coupled.

Another object of the invention is to provide the coupler with an improved valve mechanism so constructed that when the two cars are coupled the valves will be open and 25 when the cars are uncoupled the valves will be closed thus making it unnecessary to manually open and close the valves of the train pipes when coupling and uncoupling the cars.

30 Another object of the invention is to provide a train pipe coupler which will be very simple in construction and consists of a comparatively few number of parts firmly held in the proper position and thus providing a 35 strong and compact structure.

This invention is illustrated in the accompanying drawings, wherein:—

Figure 1 is a view showing the improved coupler in longitudinal section, the valves 40 being open. Fig. 2 is a view showing the improved coupler partially in longitudinal section and partially in elevation with the valves closed. Fig. 3 is a view showing the improved coupler partially in transverse 45 section and partially in end elevation. Fig. 4 is a view in elevation of the head of the coupler. Fig. 5 is a sectional view taken along the line 5—5 of Fig. 1. Fig. 6 is a sectional view taken along the line 6—6 of Fig. 1.

The barrel or body portion 10 of this coupler is provided with an enlarged inner end portion forming the chamber 11 having an inlet neck 12 and having its end closed 55 by means of the cap 13. This cap 13 carries the eye 14 with which the suspending or

supporting yoke 15 is connected. It will thus be seen that the inner end portion of the coupler will be supported by the yoke but permitted to have a certain movement 60 necessary for the proper operation of the coupler. The air hose 16 forming part of the train pipe fits upon the nipple 17 carried by the inlet neck 12 and it will thus be seen that when in use air will pass into the 65 chamber 11 through the pipe 16. The outer end portion of the chamber 11 is threaded as clearly shown in Figs. 1 and 2 so that the valve seat 18 may be screwed into place and removed when it is necessary to grind the 70 valve seat or clean the same.

The tubular stem or piston 19 is slidably mounted in the neck 20 of the barrel or body portion 10 and has its inner end portion threaded and screwed into the piston head 75 21, which piston head is positioned between the valve seat 18 and abutment ring 22. Packing 24 is provided for the piston head or collar 21 thus forming a tight joint and preventing leakage of air around the piston 80 head. The stem 25 of valve 26 is pivotally connected with the piston head 21 by means of the pins 27 and brackets 28 and it will thus be seen that the valves can be brought into very tight engagement with the valve 85 seat since it has pivotal movement and therefore if it does not strike squarely upon the valve seat it can move to the proper position to fit tightly upon the valve seat. A spring 29 is placed between the abutment 90 22 and collar 30 which collar is removably mounted upon the piston 19 and held in place by means of set screw 31. This spring normally holds the coupler in the position shown in Fig. 2 with the valve closed but 95 permits the stem or piston 19 to move inwardly as shown in Fig. 1 so that the valve 26 may be moved to the open position and air permitted to pass from the chamber 11 through the hollow piston. It will thus be 100 seen that when the cars are not coupled the valves will be closed but when the cars are coupled the valves will be open this being accomplished by pressure being applied to the piston 19 through the medium of a coupler 105 carried by an adjoining car.

The neck 20 of this coupler is engaged by the yoke 32 carried by the sleeve 33, this sleeve is slidably mounted upon the cross bar 34 positioned between the supporting 110 arms or standards 35. The standards 35 are slidably mounted in openings formed in the

upper and lower bars 36 and 37 of the hanger 38 and springs 39 and 40 are provided to yieldably hold the standards and sleeve in the normal position. Therefore, 5 although the neck and barrel of the coupler will normally remain in the position shown in the drawings, vertical and transverse movement will be permitted so that when turning a curve or when going over rough 10 roads the barrel will be permitted to have sufficient vertical and transverse movement to remain in the proper position.

The outer end portion of the piston 19 is flared and carries the ball 41 which fits into 15 the socket 42 of the coupler head and engages the gasket 43. The cap 44 of this coupler head fits about the ball 41 and is secured to the body portion of the coupler head 45 by means of the machine screws or 20 other fasteners 46. The heads of the two couplers of adjoining cars can therefore move when going around a curve or when going over a rough road without the heads of the two couplers becoming disconnected 25 and without the openings in the two couplers moving to a position which would prevent the passage of air from one coupler to the other. In order to provide a tight joint between the two coupler heads there 30 has been provided a facing 47 of rubber which facing is secured to the body portion of the coupler head by means of the inner rings 48 and outer annulars 49, the rings and annulars being secured by means of the 35 machine screws 50 and bolts 51.

I have therefore provided a train pipe coupler which is so constructed that the coupler heads mounted by means of the universal joint and the barrel is yieldably supported so that the coupler heads of the two cars will not become disconnected when turning a curve so that vertical and transverse movement may be permitted when going over a rough road. I have further provided 40 a coupler so constructed that the valves will be opened when the cars are coupled and closed when the cars are disconnected, this being automatically done and therefore makes it unnecessary for the trainman to go between the cars in order to connect the air pipes and open or close the 45 valves.

What is claimed is:—

1. A train pipe coupler comprising a barrel 55 having its inner end portion enlarged to provide a chamber, a neck connected with the opposite end portion of said barrel and provided with a passageway communicating with the interior of the barrel, a valve seat in said chamber, a hollow piston slidably mounted in said neck and extending into said barrel, a piston head carried by the inner end portion of said piston and provided with a passageway communicating 60 with the interior of the hollow piston,

a valve in said chamber having its stem pivotally mounted within said piston head, an abutment positioned in said barrel around said piston, an abutment collar carried by said piston, a spring positioned between said abutment and said abutment collar to yieldably hold said piston in an extended position with the valve engaging the valve seat, and a coupler head connected with the outer end portion of said piston. 70

2. A train pipe coupler comprising a body portion, a valve for controlling the passage of fluid through said body portion, a piston slidable in said body portion and connected with the valve whereby longitudinal movement of the piston will open and close the valve, means for yieldably holding the piston in a normal position with the valve closed, a ball carried by the outer end portion of said piston, and a coupler head carried by said ball, said coupler head comprising a body portion having a socket to receive the ball and provided with a passageway communicating with the interior of the piston, a gasket positioned in the socket and engaged by the inner end portion of the ball, a cap connected with the body portion of the coupler head and holding the body portion of the coupler head upon the ball, a facing for the body portion of said coupler, and means for holding said facing in place. 80

3. A train pipe coupler comprising a body portion, a supporting structure including upper and lower bars, standards slidably mounted between said upper and lower bars, a cross bar connecting said standards, a sleeve slidably mounted upon said cross bar, resilient means positioned between said sleeve and standards and between said cross bar and upper and lower bars to yieldably hold said sleeve and standards in a normal position, means carried by said sleeve for engaging the outer end portion of the body portion of the coupler, flexible means connected with the inner end portion of the body portion of the coupler to support the same, means for controlling the passage of air through the body portion, and a coupler head carried by said last mentioned means. 100

4. A train pipe coupling comprising a barrel having a neck provided with a passageway communicating with the interior of the barrel, a valve seat in said barrel, a hollow piston slidably mounted in said neck and extending into said barrel, a piston head carried by the inner end portion of said piston and provided with a passageway communicating with the interior of the hollow piston, a valve in said barrel having its stem connected with said piston head, means to yieldably hold said piston in an extended position with the valve engaging the valve seat, and a coupler head connected with the outer end portion of said piston. 110

5. A train pipe coupling comprising a body portion, a piston slidable in said body portion and having one end extending beyond the body portion, a ball carried by 5 the outer end portion of said piston, and a coupler head carried by said ball, said coupler head comprising a body portion having a socket to receive the ball and provided with a passageway communicating with the 10 interior of said piston, a gasket positioned in the socket and engaged by the forward portion of the ball, and a cap connected with the body portion of the coupler head and holding the body portion of the coupler 15 head upon the ball.

6. A train pipe coupler comprising a body portion, a supporting structure including a frame, standards slidably connected with

said frame for vertical sliding movement and yieldably held in a normal position, a cross bar connecting said standards, a sleeve slidably and rotatably mounted upon said cross bar, and yieldably held in a normal position, means carried by said sleeve for engaging the outer end portion of the body 20 portion of the coupler, means to movably support the inner end of the body portion of the coupler, and means for controlling the passage of air through the body portion.

In testimony whereof I affix my signature 25 in presence of two witnesses.

EDWIN K. KREBS.
